US00D560175S

(12) **United States Design Patent** (10) **Patent No.:** **US D560,175 S**
Commare et al. (45) **Date of Patent:** **** Jan. 22, 2008**

(54) **POWER CONTROLLER USER INTERFACE
BUTTON**

(75) Inventors: **Donald L. Commare**, La Crescent, MN (US); **Craig R. Dennis**, Winona, MN (US); **Thomas R. Pfingsten**, Winona, MN (US)

(73) Assignee: **Watlow Electric Manufacturing Company**, St. Louis, MO (US)

(**) Term: **14 Years**

(21) Appl. No.: **29/252,397**

(22) Filed: **Jan. 20, 2006**

(51) **LOC (8) Cl.** **13-03**

(52) **U.S. Cl.** **D13/174**

(58) **Field of Classification Search** ..... D13/125, D13/158-177, 184, 199; D14/218, 239; 715/716; 200/310, 314, 329, 4, 406, 524, 200/530, 532, 536, 6, 6 A, 8, 1 R, 5 R

(57) **CLAIM**

The ornamental design for a power controller user interface button, as shown and described.

DESCRIPTION

FIG. 1 is a perspective view of a power controller interface button showing our new design; and,

FIG. 2 is a front view thereof.

The broken lines are included for the purpose of illustrating environmental structure and form no part of the claimed design.

1 Claim, 2 Drawing Sheets

FIG. 1

FIG. 2
